(57) **CLAIM**

I claim the ornamental design for a two-piece surgical blade handle adapter, as shown and described.

DESCRIPTION

FIG. 1 is a side elevational view in an assembled state of a two-piece surgical blade handle adapter showing an upper portion and a lower portion;

FIG. 2 is a front view thereof;

FIG. 3 is a side elevational view thereof;

FIG. 4 is a bottom view thereof;

FIG. 5 is a bottom perspective view thereof;

FIG. 6 is a top plan view of the top piece of the two-piece surgical blade handle adapter shown detached for ease of illustration;

FIG. 7 is a side elevational view thereof;

FIG. 8 is a cross-sectional view thereof taken along line 8-8 of FIG. 7;

FIG. 9 is a bottom view thereof;

FIG. 10 is a bottom view thereof;

FIG. 11 is a top perspective view thereof;

FIG. 12 is a top plan view of the bottom piece of the two-piece surgical blade handle adapter shown detached for ease of illustration;

FIG. 13 is a side elevational view thereof;

FIG. 14 is a bottom view thereof;

FIG. 15 is a top plan view thereof;

FIG. 16 is a side elevational view thereof; and,

FIG. 17 is a bottom view thereof.

The broken lines in FIG. 1 of the drawings show unclaimed environment only and form no part of the claimed design.

1 Claim, 4 Drawing Sheets
